Primary Examiner — Ricky Pham(74) *Attorney, Agent, or Firm* — Connolly Bove Lodge & Hutz LLP(57) **CLAIM**

The ornamental design for the macaroon baking sheet, as shown and described.

DESCRIPTION

FIG. 1 is a perspective view of the macaroon baking sheet; FIG. 2 is a front elevation view of the macaroon baking sheet; FIG. 3 is a cross-sectional view of the macaroon baking sheet along 3-3 of FIG. 2;

FIG. 4 is an enlarged cross sectional view of a segment of the macaroon baking sheet taken from line 4 of FIG. 3 to the end on the right side of the macaroon baking sheet; and, FIG. 5 is a rear elevation view of the macaroon baking sheet.
